WIRE DRAWING APPARATUS

Edwin J. McIlvried, Akron, and Jesse C. Bittman, Cuyahoga Falls, Ohio, assignors to The Vaughn Machinery Company, Cuyahoga Falls, Ohio, a corporation of Ohio

Application July 26, 1930, Serial No. 470,892

16 Claims. (Cl. 205—16)

This invention relates to apparatus for working material in strand or strip form, and more particularly our invention relates to a novel form of wire drawing machine.

5 The principal object of our invention is to provide improved wire drawing apparatus in which novel means is employed for tensioning the strand issuing from the working means; in which automatic strand gripping means is provided for preventing withdrawal of the issuing strand into the casing housing the working means; in which jaw means is provided for gripping the issuing strand when the tension thereof is relieved; in which novel means is provided for applying a compound-removing and drying agent to the strand issuing from the working means; and in which the slot for threading the strand through the drying means is provided with novel cover means.

20 The die arrangement herein disclosed, but not claimed, is claimed in co-pending application Serial Number 562,329, filed September 11, 1931, and the compound distributing means herein disclosed, but not claimed, is claimed in co-pending application Serial Number 562,328, filed September 11, 1931.

Other objects and advantages of the invention will be apparent from the following description when taken in conjunction with the accompanying sheets of drawings, in which

30 Fig. 1 is a side elevational view of wire drawing machinery embodying our invention.

Fig. 2 is a top plan view thereof.

Fig. 3 is a top plan view of the strand tensioning and gripping device with parts thereof in section.

Fig. 4 is a side elevational view thereof.

Fig. 5 is an end view of the strand tensioning and gripping device taken in the direction indicated by the line 5—5 of Fig. 2.

40 Fig. 6 is an elevational view taken in the direction indicated by line 6—6 of Fig. 3.

Fig. 7 is an end elevational view of the tensioning device showing the sheave guard.

45 Fig. 8 is a partial side elevation on an enlarged scale, showing the releasing mechanism for the strand gripping means.

Fig. 9 is partial sectional plan view showing the arrangement of fluid passages in the drying device, and

50 Fig. 10 is a sectional elevation taken on line 10—10 of Fig. 9.

In the drawings, to which detailed reference will now be made, we have shown our invention embodied in wire drawing apparatus which is

suitable for high speed operation. It should be understood, however, that our invention may also be used in connection with various kinds of machinery for the drawing or working of material supplied thereto in strand or strip form.

60 In the apparatus which we have illustrated, we have shown strand working machinery 10, to which material to be worked is supplied in strand or strip form, and from which the strand of worked material is delivered to suitable spooling means 11. The strand working means housed within the casing 12, embodies a series of suitable dies 13, which are supported upon the die bracket or shelf 14, and through which the strand is drawn by means of the rotatable drawing capstans 15 and 16. On the side of the die bracket opposite that on which the drawing capstans 15 and 16 are arranged, we provide an idler capstan 17 having a plurality of flanged and independently rotatable idler sheaves 18 around which the strand passes. The drawing capstans 15 and 16 are arranged in axial alignment with each other, and by suitable driving means (not shown) are adapted to be rotated in the same direction but at different speeds. The drawing 70 capstans are of well known construction, being made up of step-like arrangements of annular drums of different diameters. The varying drum diameters of these capstans, and the provision for different speeds of rotation thereof, take care 80 of the increase in the length of the strand, which results from its passage through the dies.

85 In wire drawing machinery as heretofore constructed, it has been common to provide a rotating die for finishing the strand being worked. It has been customary, however, to mount this finishing die independently of the die bracket which supports the working dies. In our strand working apparatus as herein illustrated, we mount the rotatable finishing die 26 at the outer 95 end of the die bracket 14, and extend a shaft through the die bracket for operating the rotary die from the electric motor 32.

We have designated the strand, being worked by the reference character 37, and as represented 100 in Figs. 1 and 2 of the drawings, this strand passes from the working means to the spooling means 11 where it is taken up by a suitable reeling operation, such as by being wound upon the spool 38. In the operation of apparatus of this kind, 105 it is desirable that the strand of material passing from the working means to the spooling means be maintained under tension and, for this purpose, we provide the tensioning device which is indicated generally by the reference character 39. 110

In addition to its function as a tensioning means, this device also serves as a guide means which changes the direction of travel of the issuing strand, and permits the spool 38 to be located 5 near the floor upon which the machine is supported so that lifting of spools through appreciable distances is avoided.

The tensioning device is mounted upon the end wall of the casing 12 in such a manner that the 10 idler sheave 40 thereof is movable in a vertical plane. This idler sheave is mounted for rotation upon the anti-friction bearings 41 which are arranged upon the shaft 42. This shaft is mounted in the head portion 43 of the movable 15 bracket 44 so as to extend in a substantially horizontal plane, and is retained in the head portion by suitable means, such as the pin 45 which extends through the shaft. The end of the bracket 44 opposite the head portion 43 thereof is pivotally mounted upon the shaft 46, which is supported by suitable bracket means 47 secured to the end wall of the casing 12. For moving the bracket 44 so as to impart movement to the sheave 40 in a direction to increase the tension 20 on the issuing strand, we provide suitable means which normally tends to swing the bracket in an upward direction. While any suitable means may be employed for this purpose, we prefer to use a coil spring 48, which surrounds the shaft 46, and 25 has one end thereof secured to the stationary bracket 47 and the other end thereof secured to the movable bracket 44. When the device is assembled, the spring 45 is initially stressed so that thereafter it always tends to swing the movable bracket upwardly about the shaft 46.

During the operation of apparatus of this kind, the strand of material being wound upon the spool frequently breaks, and to prevent the issuing strand from being withdrawn into the casing 40 which houses the working means, we provide a device 50 for automatically gripping the strand as soon as the tension thereof is relieved. This automatic gripping means comprises a substantially funnel-shaped body member 51, having 45 a tapered tubular passage 52 through which the issuing strand travels. To provide for movement of the gripping device in a vertical plane with the tensioning sheave 40, we support the body member 51 by securing the same to one end of the 50 arm 53. At the other end of this arm, we provide an enlargement or head portion 54, having anti-friction bearings 55 assembled therein for rotatably mounting the arm 53 upon the idler shaft 42. It will thus be seen that as the sheave 55 of the tensioning device moves up and down in a vertical plane, the body member 51 of the gripping device also moves up and down in a vertical plane.

It will be noted that, as shown in Fig. 4, the 60 axis of the body member 51 is substantially tangent to the bottom of the groove, of the sheave so that, in passing from the capstan 16 of the working means to the sheave of the tensioning means, the strand passes through the body member in a straight line and is not subjected to deflection or bending. For maintaining this straight line relationship between these three elements, namely the capstan 16, the sheave 40 and the axis of the body member 51, we provide suitable linkage 65 resembling a pantograph arrangement which has the effect of maintaining the body member at all times in a position with respect to the sheave and the capstan such that its axis is always tangent to the two latter members regardless of the different 70 positions which the body member and the sheave 75

may assume in the vertical plane. The resulting movement for the sheave and for the body member which we have just described, is brought about by the use of the connecting link 56 in conjunction with the swinging bracket 44. The connecting link is arranged with one end thereof pivoted to the casing 12, and the other end thereof pivotally connected to the arm 57, which is formed integral with the head portion 54 of the arm 53. It will be seen from this arrangement 80 that, as the sheave 40 is moved up and down in the vertical plane by the swinging of the bracket 44 about its shaft 46, the link 56 imparts movement to the arm 53 causing it to swing upon the bearings 55 through a sufficiently great angular 85 distance to maintain the axis of the body member 51 in a straight line position, which is always tangent to the sheave and to the capstan 16.

It will be noted that the body member 51 of the clamping device extends through a slot provided in the end wall of the casing 12 with the flaring disc portion 58 within the casing. If desired, a flexible sealing gasket, such as the rubber sheet 59, may be provided to prevent the escape of fluid through the slot of the casing wall. 90 This flexible sealing member is formed with a vertical slit through which the body member 51 of the gripping device extends. The flexible sealing gasket permits vertical movement of the gripping device in the vertical slot, but tends to 95 close the slot through the casing wall at points above and below the body member.

As already stated the body member 51 is carried upwardly and downwardly simultaneously with the sheave by the swinging movement of the 100 bracket 44. It has also been pointed out how, under the influence of the link 56, the body member is tilted during its upward and downward movement so as to maintain its axis tangent to the sheave 40 and to the capstan 16. However, in 110 securing the correct positioning of the axis of the body member during its upward and downward movement, the link 56 also causes this member to be moved axially to some extent. That is to say, as the body member is moved upwardly it 115 is also moved farther into the casing 12, and as the body member is carried downwardly it is moved in a direction tending to withdraw it from the casing.

The mechanism of the gripping means is carried 120 by the outwardly flaring disc portion 58 of the body member 51. This mechanism includes a pair of movable jaws 60 and 61, which are provided with hardened contact elements 62 for engagement with the strand. These jaws are mounted 125 for swinging movement by being secured to substantially parallel vertical shafts 63, which are journaled in the pairs of aligned brackets 64 which extend laterally from the disc portion 58. It will be noted that the straight line distance between the axes of the vertical shafts 63 is somewhat less than the combined length of the two jaws 60 and 61 so that when these jaws are moved 130 toward each other to close upon the strand they do not assume a straight line position and, accordingly, an increasing pull upon the strand tends to move the jaws toward a straight line position with the result that the strand is more securely gripped by the contact elements 62.

For retaining the jaws 60 and 61 in proper co- 140 operating relationship, we construct these members with sectors or racks 65 which are preferably integral with the jaws and have interengaging teeth so that the jaws must move simultaneously and cannot move independently of each other. 145

In addition to their function of maintaining the cooperating jaws in proper relationship, these racks also provide a means for moving the jaws to open and closed position. To impart movement to the racks so as to actuate the jaws in a direction to cause them to close upon the strand, we provide a spring 66 having the opposite ends thereof secured to pins 70, projecting downwardly from the underside of the racks. This spring 10 is under tension and normally tends to swing the jaws towards each other and into engagement with the strand.

Movement of the jaws to the open position is attained by providing the jaw 61 with an actuating roller or cam follower 71 which is so arranged that it will engage the inclined surface of the cam 72 secured to the wall of the casing 12. When the jaws of the gripping device are to be set in the open position, the operator swings the bracket 20 44 downwardly against the action of the spring 48. The downward movement of the bracket moves the body member 51 downwardly and also moves it in a direction tending to withdraw it from the casing. The downward and outward movement of the body member causes the jaws 60 and 61 to be opened by the engagement of the follower 71 with the cam 72.

For releasably retaining the jaws in the open position against the action of the spring 66, we provide locking mechanism which is best illustrated in Fig. 8 of the drawings. This locking mechanism comprises a vertically reciprocable plunger 73 which is guided at its lower end by one of the brackets 64 and at its upper end by the laterally extending bracket 74. This plunger functions in the manner of a sliding bolt, and is of sufficient length so that when moved downwardly its lower end extends through the bracket 64 into a recess provided in the jaw 61. A coil spring 75 which surrounds the plunger, abuts against the bracket 74 and normally presses the plunger downwardly so that when the jaws are swung to the open position, the plunger will snap into the recess of the jaw 61 and will retain the jaws in the open position. For moving the plunger 73 upwardly against the action of the spring 75, so as to retract the same from the recess of the jaw 61 and thus release the jaws so that they can be quickly moved to closed position by the spring 66, we provide a trip member 50 76 which is pivotally supported at its center upon the pin 77. One end of the trip member is constructed in the form of a fork, having pairs of vertically aligned tines 78, which straddle the plunger 73. For operably connecting the fork of the trip member with the plunger so that the latter can be moved upwardly against the action of the spring 75 by tilting the trip member about its pivot 77, we provide the plunger with a transverse pin 79, which extends between the vertically aligned tines 78.

When the strand breaks during the operation of the wire drawing machine, the tension being suddenly relieved, the bracket 44 lifts the sheave 40 and the gripping device upwardly. The link 56 affects the movement of the gripping device in the manner already explained, so that simultaneously with its upward movement it is also moved laterally further into the casing 12. This upward and inward movement of the gripping device brings the end portion 80 of the trip member 76 into engagement with the abutment member 81, mounted upon the wall of the casing. This abutment may be of any desired form, but is here shown as a set screw which is adjustably

secured to the bracket 82 by means of the lock nut 83. The engagement of the trip member with the abutment member tilts the trip member about its pivot pin, causing the plunger to be moved upwardly against the spring 75. The upward movement of the plunger retracts its lower end from the recess of the jaw 61 and thus permits the spring 66 to swing the jaws toward each other and into engagement with the strand. It will be seen that by this arrangement, the jaws are retained in open position during normal operation of the machine and substantially simultaneously with the relieving of the tension of the strand incident to the breaking or cutting thereof, the jaws are released and moved into effective gripping engagement with the strand so as to prevent the latter from being withdrawn into the casing where it would become snarled and tangled around the apparatus housed therein.

As is well understood in the operation of wire drawing machinery, slippage occurs between the strand and the drawing capstans, and it is customary to use a fluid which is commonly called a "compound" which acts as a lubricant and cooling medium for the working of the strand. For supplying compound to the drawing capstans 15 and 16 of the present arrangement we provide the die bracket 14 with a row of nozzles 89 which are spaced to correspond with the spacing of the annular surfaces of the capstans. These nozzles are mounted on the side of the die bracket which is nearest the drawing capstans, as shown in Fig. 2, and are arranged to direct streams of compound against the capstan surfaces.

As the strand issues from the working means 110 and from the casing 12 some of the compound clings to the surface of the strand. For drying the strand, or removing therefrom as much as possible of the compound before the strand passes to the spool, we provide means for applying a drying agent to the strand while it is in motion. As the drying agent, we prefer to use a fluid such as compressed air and for directing this fluid against the strand we provide the body member of the gripping device with an extension 115 95 having a passage therethrough which aligns with the passage 52 of the body member 51. The walls of the extension are provided with fluid channels 96 which extend substantially parallel to the axis of the extension. Fluid is supplied 120 to these channels by suitable means, such as the flexible conduit 97. From the channels 96 the fluid is directed inwardly against the strand moving through the passage of the extension, by means of a plurality of delivery passages 98. It will be noted that, as clearly shown in Fig. 9, the delivery passages 98 do not extend in a true radial direction with respect to the axis of the extension, but are inclined so that the direction of the streams or jets of fluid, is inwardly toward the strand and is also toward the casing from which the strand issues. By inclining these delivery passages in the direction from which the strand moves, the jets of fluid delivered thereby are not only more effective in removing compound from the strand, but also blow the compound back into the casing.

As the issuing strand passes over the sheave 40 its direction of travel is changed, as indicated in Fig. 4, and some of the compound still clinging to the strand is thrown off at this point. For collecting this compound so that it can be returned to the casing, and for preventing the compound from being thrown onto other parts of the apparatus, we provide an arcuate guard 99 which 145 150

extends circumferentially a part of the way around this sheave. This guard may be of any suitable form and is preferably spaced from the sheave 40 a distance which will permit insertion 5 of the wire into the groove of the sheave by passing it under the guard, and yet spaced sufficiently close to the sheave to collect the compound thrown off the strand. During the functioning of the tensioning device, the sheave swings upwardly and 10 downwardly in the vertical plane and to prevent the guard from being moved into the path of the strand, it is necessary to provide for adjustment of the guard so as to keep it adjacent or opposite the portion of the sheave with which the strand 15 contacts. To achieve this result, we mount the guard upon the head portion 43 of the movable bracket 44 so that the guard will be rotatable around the same axis as that about which the sheave rotates. The guard is constructed with 20 an integral depending arm 100 which is of sufficient length to extend radially outwardly beyond the edge of the sheave. This radially extending arm of the guard aligns with the radially projecting portion 101 of the arm 57. A suitable connecting member such as the bar 102 extends between the arm 100 and the portion 101, so that upon movement of the bracket 43 about the shaft 46, the link 56 will cause the guard 99 to be swung and correctly positioned circumferentially of the 25 sheave. In addition to its function of collecting the compound thrown off the strand, the guard also serves to prevent the strand from jumping off of the sheave.

To enable the machine operator to quickly 30 thread the strand of material through the drying and gripping devices, we provide the body member 51 and the extension 95 with a radial slot 103. When the strand is to be threaded through the gripping and drying devices, it is inserted downwardly through this slot. For closing a portion 35 of this slot so as to prevent the escape of drying agent therethrough, we provide a cover 104 which is hinged to the extension portion 95. To prevent accidental opening of the cover, and to facilitate 40 the insertion of the strand into the slot 103, we provide the cover with a hook-like portion or extension 105 which is arranged to sweep across the end face of the extension 95. When 45 the strand is to be threaded through the gripping and drying device, the cover is in the open position and upon downward movement of the strand toward the slot 103, the operator catches the strand in the hook-like portion 50 105 thereby swinging the cover to closed position 55 as the strand moves downwardly into the slot. The hook-like portion effectively retains the cover in the closed position since it is beneath the strand and any accidental movement of the cover towards open position causes the hook-like portion to be 60 lifted into engagement with the strand.

While we have illustrated and described the apparatus of our invention in a detailed manner, it should be understood, however, that we do not intend to limit ourselves to the precise details and 65 arrangements of parts shown and described, but regard our invention as including such changes and modifications as do not involve a departure from the spirit of the invention and the scope of the appended claims.

70 Having thus described our invention, we claim:
 1. In apparatus of the character described the combination of means for delivering a strand of material, means for reeling the strand issuing from said delivery means, movable means for tensioning said strand, and means movable with said

tensioning means for removing material from said strand as it passes from said delivering means to the reeling means including a member having a passage for directing fluid against said strand at an angle which is acute to the axis of the strand. 80

2. In apparatus of the character described the combination of means for delivering a strand of material having fluid adhering thereto means for reeling the strand issuing from said delivering means, movable means for automatically gripping the strand when the same is cut or broken, and means movable with said gripping means for drying said strand including a member through which said strand passes, said member being provided with means for directing a drying agent toward said strand and in the direction from which the strand is moving. 90

3. In apparatus of the character described the combination of means including a rotatable element for delivering a strand of material, means for reeling the strand issuing from said delivery means, movable means intermediate said delivery means and said reeling means for guiding and tensioning said strand, means for applying a drying agent to said strand including a member having a passage therethrough, and means movably supporting said member so as to maintain the axis of said passage substantially tangent to said rotatable element and said movable means. 100

4. In apparatus of the character described the combination of means for delivering a strand of material, means for reeling the strand issuing from said delivery means, a rotatable member over which said strand passes, movable supporting means for said rotatable member whereby the latter can be moved to tension said strand, a member adjacent said rotatable member having means for applying a drying agent to said strand, and means connecting the last mentioned member with said movable supporting means. 110

5. In apparatus of the character described the combination of means including a rotatable element for delivering a strand of material, means for reeling the strand issuing from said delivery means, movable means intermediate said delivery means and said reeling means for guiding and tensioning said strand, means for gripping said strand when the tension thereof is relieved including a member having a passage therethrough, and means movably supporting said member so as to maintain the axis of said passage substantially tangent to said rotatable element and said movable means. 120

6. In apparatus of the character described the combination of a casing, means in said casing for delivering a strand of material, means for reeling the strand issuing from said delivering means, means for tensioning said strand including a sheave and a movable support therefor, and means carried by said support for automatically gripping said strand to prevent withdrawal thereof into said casing, said gripping means comprising a pair of movable jaws, gear means operably connecting said jaws, means for urging said jaws to close on said strand, an actuating member associated with one of said jaws, means on said casing adapted to be engaged by said actuating member for opening said jaws, and means for releasably locking said jaws in the open position. 130

7. In apparatus of the character described the combination of a casing, means in said casing for delivering a strand of material, means for reeling the strand issuing from said delivering means, and means for gripping said strand to 140 145 150

- prevent the withdrawal thereof into said casing, said gripping means comprising relatively movable cooperating jaws means, means for urging said jaw means to close on said strand, and means adapted to lock said jaw means in the open position and means rendered effective for releasing the jaw means when the continuity of said strand is interrupted. 5
8. In apparatus of the character described the combination of means for delivering a strand of material, means for reeling the strand issuing from said delivering means, means including a movable arm for tensioning the issuing strand, and means carried by said movable arm for automatically gripping the issuing strand when the tension thereof is relieved, said gripping means comprising movable jaw means, means for urging said jaw means to close on said strand, means for releasably locking said jaw means in the open position including a trip member, and stationary abutment means adapted to be engaged by said trip member to release said jaw means. 10
9. In apparatus of the character described the combination with a member having a passage through which a strand moves and a slot for threading the strand into said passage, of a hinged cover for said slot, and means on said cover adapted to be engaged by said strand whereby the cover is swung to close said slot upon the threading of the strand therethrough. 15
10. In apparatus of the character described the combination with a member having a passage through which a strand moves and a slot for threading the strand into said passage, of a movable cover for said slot, and a hook-like extension on said cover adapted to be engaged by said strand for moving the cover to close said slot. 20
11. In apparatus of the character described the combination with a member having a passage through which a strand moves and a slot for threading the strand into said passage, of a movable cover for said slot, and means on said cover extending beneath said strand to prevent accidental opening of the cover. 25
12. In apparatus of the character described, the combination with a casing having strand delivery means therein, of a gripping device movable relative to said casing and having strand engaging means adapted to be moved from an open position into engagement with the strand issuing from said delivery means upon movement of the device in one direction, and means adapted to be engaged upon movement of said gripping device in another direction for moving said strand engaging means to the open position. 30
13. In apparatus of the character described the combination of means for delivering a strand of material, means for reeling the strand issuing from said delivering means, shiftable means intermediate the delivering means and said reeling means for automatically gripping the issuing strand when the continuity of the same is interrupted, means for setting said gripping means including an actuating member shiftable with the gripping means and a stationary member adapted to be engaged by said actuating member, and means for releasing said gripping means. 35
14. In apparatus of the character described the combination of means for delivering a strand of material, means for reeling the strand issuing from said delivering means, shiftable means intermediate the delivering means and the reeling means for tensioning the issuing strand, means shiftable with said tensioning means for automatically gripping the issuing strand when the tension of the same is relieved, means for setting said gripping means including an actuating member shiftable with the gripping means and a stationary cam adapted to be engaged by said actuating member, and means for releasing said gripping means including a trip shiftable with the gripping means, and means for actuating the trip upon shifting of the gripping means through a predetermined distance. 40
15. In apparatus of the character described the combination of means for delivering a strand of material, means for reeling the strand issuing from said delivering means, shiftable means intermediate the delivering means and the winding means for tensioning the issuing strand, and means shiftable with said tensioning means for automatically gripping the issuing strand when the tension of the same is relieved, said gripping means comprising relatively movable cooperating jaw means, means for urging said jaw means toward a strand engaging position, means for setting said jaw means in a normally open position including a jaw actuating member and a stationary cam adapted to be traversed by said jaw actuating member, and means for releasing said gripping means including a trip shiftable with the gripping means and a stationary abutment adapted to be engaged by said trip. 45
16. In apparatus of the character described the combination of means for delivering a strand of material, means for reeling the strand issuing from said delivering means, shiftable means intermediate the delivering means and the winding means for tensioning the issuing strand, and means shiftable with said tensioning means for automatically gripping the issuing strand when the tension of the same is relieved, said gripping means comprising relatively movable cooperating jaw means, spring means normally urging said jaw means to close on said strand, means for opening said jaw means in opposition to said spring means including a jaw actuating member and a stationary cam adapted to be traversed by said jaw actuating member, means adapted to lock said jaw means in the open position, and means for releasing the jaw means for actuation by said spring means when the tension of the strand is relieved including a trip and a stationary abutment adapted to be engaged by said trip. 50
